UNITED STATES PATENT OFFICE.

GEORGE D. HOFFMAN, OF PASADENA, CALIFORNIA, ASSIGNOR TO HOFFMAN SPECIALTY COMPANY, OF BOSTON, MASSACHUSETTS, A CORPORATION OF MASSACHUSETTS.

RADIATOR AIR-VALVE.

1,132,010.

Specification of Letters Patent. Patented Mar. 16, 1915.

Application filed May 25, 1914. Serial No. 840,765.

To all whom it may concern:

Be it known that I, GEORGE D. HOFFMAN, a citizen of the United States, and resident of Pasadena, in the county of Los Angeles and State of California, have invented certain new and useful Improvements in Radiator Air-Valves, of which the following is a specification.

This invention relates to valves permitting the escape of cold air displaced in steam radiators by steam pressure, and closing automatically to prevent the escape of water and steam, the valve casing being provided with a siphonic draining stem entering the radiator. The invention has for its object to provide improved means for connecting the stem with the casing, and at the same time forming a space for the admission of air from the radiator into the valve casing.

The invention consists in the improvements which I will now proceed to describe and claim.

Of the accompanying drawings: Figure 1 represents a side elevation of an air valve embodying my invention; Fig. 2 represents an enlarged longitudinal section of the same; Fig. 3 represents a section on line 3—3 of Fig. 2; Fig. 4 represents in perspective the draining stem hereinafter referred to, and the other parts which operate with said stem and with the casing and its nipple in forming the independent conduits hereinafter described for air and water, said parts being disconnected; Fig. 5 represents a side view of a portion of the draining stem and a sectional view of the flexible seat with which said stem is loosely connected; Fig. 6 represents a sectional view illustrating the operation of inserting the draining stem; Fig. 7 represents a fragmentary sectional view, showing a modification; Fig. 8 represents a side view of the part called the seat member, showing the lower edge of said member slightly curved.

The same reference characters indicate the same parts in all the figures.

The casing of my improved air valve is composed of a lower or base member and an upper member, said members detachably connected. The base member comprises a bottom 13 and a circular wall 14 rising from the bottom and internally screw-threaded

at 15 to engage an external thread on the upper casing member 16. To the wall 14 of the base member is attached a screw-threaded nipple 17 adapted to engage a tapped orifice in a steam radiator.

19 represents a float which is provided at its upper end with an acting valve member 19^a adapted to close an air vent 16^a in the contracted or domed upper end of the casing member 16, and at its lower end with a flexible diaphragm 19^b bearing on the raised center of the bottom 13, which is substantially conical. The diaphragm is adapted to be flexed downwardly by the expansion of a volatile liquid such as alcohol contained in the hermetically sealed float, thus raising the float and closing the valve member 19^a, such expansion being caused by the entrance of steam into the casing. The float is also adapted to be raised to close the valve member, by an accumulation of water on the bottom of the casing.

23 represents a curved tubular draining stem formed to extend through the nipple 17 into the radiator and to project downwardly from the nipple as shown, said stem being adapted to conduct water from the casing to a point below a current of air entering the nipple from the radiator.

In the preferred embodiment of my invention shown by Figs. 2, 3, 4 and 5, the stem 23 is connected with the base member 85 of the casing by a seat member 25 composed of a metal strip having curved end portions and a straight central portion containing an orifice to receive the draining stem, and an annular countersunk seat 26 surrounding 90 said orifice, said strip forming one side of an air space 22, communicating with the bore of the nipple 17, as shown by Figs. 2 and 3.

The draining stem 23 passes loosely 95 through the orifice in the seat member 25 and has a flange 27 at its inner end formed to fit the seat 26.

When the members of the casing are separated, the stem 23 and seat member 25, assembled as indicated by Fig. 5, may be introduced together into the casing member 14, the curvature of the stem being such that the stem is adapted to be inserted in the nipple 17 while turned upside down, as 105 shown by Fig. 6, the stem being moved in

the direction indicated by the arrow until its flange 27 bears on the seat 26, and then turned to the position shown by Figs. 1 and 2. The seat member 25 may be then confined by a curb 20 formed by a resilient strip of metal having a straight central portion containing an orifice 21, and curved portions having overlapping ends and forming collectively a segmental expansible curb portion which is pressed outwardly against the wall of the casing member 14 by the resilience of the strip, the straight portion of the strip being formed to bear on the straight portion of the seat member 25. 10 The orifice 21 in the curb coincides with the passage in the stem 23 and its diameter is less than that of the flange 27, so that the curb presses the flange against the seat 26, and maintains a practically air- and liquid-tight connection between the flange and seat. 15 The normal diameter of the curb 20 is such that it has to be compressed before entering the casing member 14. The previously inserted seat member indicates the proper location of the curb to cause its orifice 21 to coincide with the stem 23. The effort of the compressed curb to expand when inserted in the casing member 14 causes a close frictional engagement of the 20 curb with the casing member, so that when the curb has been pressed down to place its lower edge in close contact with the bottom 13. The effort of the curb to expand also presses its straight central portion against the stem flange 27.

It will now be seen that the seat member 25, the stem 23, and the base member 14, may be conveniently assembled and that the seat member and stem may then be conveniently secured to or confined in the base member. 40

The general operation of the valve is the same as in other valves of this class. The float is adapted to be raised and caused to 45 close the air vent by water entering the float chamber through the stem 23 when the water is under steam pressure and before it regains its equilibrium. The deflection of the diaphragm 19^b, which takes 50 place when steam reaches the casing, lifts the float and closes the air vent.

The detachable frictionally secured seat member and the draining stem 23 separably engaged therewith constitute a simple and 55 effective means for subdividing the interior of the casing member 14 and nipple 17 into independent conduits or passages for water and air.

I do not limit myself to a construction in 60 which the flange 27 of the draining stem is clamped between the curb and a seat behind it.

The seat member 25 may be omitted and 65 the flange 27 seated on the inner surface of the straight portion of the curb, which con-

stitutes an equivalent seat member, as shown by Fig. 7, the flange being soldered or otherwise secured to the curb if desired, in which case the draining stem should be made in two parts, one adapted to turn on 70 the other as shown by my pending application filed March 29, 1913, Serial No. 757,581, to enable the part which extends into the radiator to constantly project downwardly while the valve is being revolved to screw 75 the nipple 17 into the radiator.

I prefer the construction which includes the seat member 26, because this construction enables the draining stem to be made in one piece, the seat 26 being rotatable 80 relatively to the flange 27.

It is obvious that the strip of which the curb is made may be considerably wider than here shown to increase the height of the curb and that the lower edges of the 85 straight portions of the curb and seat member may be slightly curved to enable them to accurately fit the convex curvature of the portion of the bottom 13 on which they bear. This curvature is shown between the 90 points α — α (Fig. 8), which is a view of the inner side of the seat member 25. The lower edge of the straight portion of the curb may be similarly curved.

Having described my invention, I claim: 95

1. An air valve comprising a casing composed of separable upper and lower members, a radiator-engaging nipple attached to the lower member, a seat member having end portions bearing on the wall of the 100 lower casing member and an intermediate portion provided with an orifice and separated from said wall by an air space which communicates with the nipple, and a curved draining stem engaged with said seat member and extending therefrom through the air space and nipple, the said seat member and stem being insertible together in the lower casing member. 105

2. An air valve comprising a casing composed of separable upper and lower members, a radiator-engaging nipple attached to the lower member, an expansible curb bearing on the bottom of the lower member and having resilient curved portions 115 bearing yieldingly on the wall of said member, and an intermediate seat portion provided with an orifice and separated from said wall by an air space which communicates with the nipple, and a curved draining stem engaged with the curb and extending therefrom through the air space and nipple. 120

3. An air valve comprising a casing composed of separable upper and lower members, a radiator-engaging nipple attached to the lower member, an expansible curb bearing on the bottom of the lower member and having resilient curved portions bearing yieldingly on the wall of said member, 125

and an intermediate portion provided with an orifice and separated from said wall by an air space which communicates with the nipple, a seat member bearing on a portion of the curb and forming one side of said air space and provided with an annular seat surrounding an orifice which coincides with the orifice in the curb, and a

curved draining stem having a flange pressed by the curb against said seat. 10

In testimony whereof I have affixed my signature, in presence of two witnesses.

GEORGE D. HOFFMAN.
